(57) **CLAIM**

The ornamental design for a display box, substantially as shown and described.

DESCRIPTION

FIG. 1 is a perspective view of the front, top, and left side of the display box with the interior exposed, showing our new design;

FIG. 2 is a perspective view of the rear, top, and right side thereof;

FIG. 3 is a front elevational view thereof;

FIG. 4 is a side elevational view of the right side of the display box, the left side being a mirror image thereof;

FIG. 5 is a rear elevational view thereof;

FIG. 6 is a top plan view thereof; and,

FIG. 7 is a bottom plan view thereof.
